(57) **CLAIM**

The ornamental design for a novelty creature coin dispenser bank, as shown and described.

DESCRIPTION

FIG. 1 is a front elevational view of a novelty creature coin dispenser bank showing my new design;

FIG. 2 is a bottom plan view thereof;

FIG. 3 is a right side elevational view thereof;

FIG. 4 is a left side elevational view thereof;

FIG. 5 is a front end elevational view thereof;

FIG. 6 is an opposite end elevational view thereof; and,

FIG. 7 is a cross sectional view taken along line 2—2 of FIG. 7.

The broken line showing of the environment is for illustrative purposes only and forms no part of the claimed design.
